Doris Benjamin

UNITED STATES PATENT OFFICE.

DOROTHY P. BENJAMIN, OF NEW YORK, N. Y.

DESIGN FOR A YARN-BALL HOLDER.

48,542.

Specification for Design.

Patented Feb. 15, 1916.

Application filed December 4, 1915. Serial No. 65,144. Term of patent 3½ years.

To all whom it may concern:

Be it known that I, DOROTHY P. BENJAMIN, a citizen of the United States, residing at New York, in the county of New York and State of New York, have invented a new, original, and ornamental Design for Yarn-Ball Holders, of which the following is a specification, reference being had to the accompanying drawing, forming part thereof.

The figure is an elevation of a yarn ball holder, showing my new design.

I claim:

The ornamental design for a yarn ball holder, as shown.

DOROTHY P. BENJAMIN.

Witnesses:

GERTRUDE T. PORTER,
MAY T. McGARRY.
